(57) **CLAIM**

The ornamental design for a tablet computer, as shown and described.

DESCRIPTION

FIG. 1 is a front perspective view of a tablet computer in accordance with the new design.

FIG. 2 is a front view thereof.

FIG. 3 is a back view thereof.

FIG. 4 is a first side view thereof.

FIG. 5 is a second side view thereof.

FIG. 6 is a top view thereof.

FIG. 7 is a bottom view thereof.

FIG. 8 is a back perspective view thereof.

FIG. 9 is a side perspective view thereof, shown on a table top.

FIG. 10 is a front and side perspective view thereof.

The broken lines shown in the drawings represent portions of the tablet computer that form no part of the claimed design.

The broken lines showing a table top in FIGS. 9 and 10 represent environment of the tablet computer and form no part of the claimed design.
